UNITED STATES PATENT OFFICE

2,613,937

TOY HOUSE MARBLE GAME

Ralph A. Kitson, Hull, Mass.

Application March 17, 1948, Serial No. 15,379

1 Claim. (Cl. 273—120)

1

The present invention relates to games and the like and it relates more particularly to marble games.

It is an object of the present invention to provide a gaming device for marbles and the like, in the form of a demountable toy house.

Another object of the invention is the provision of a simple and easily assembled structure for use as a ball or marble game, and also as an attractive building toy.

Stated broadly, the present invention provides a knockdown structure having a chimney member forming a vertical conductor adapted for the passage of spherical objects in free fall therethrough, means within the erected structure and in the path of said free fall for altering said path, arresting and conducting means beneath said paths, and passages adjacent said conducting means leading to compartments outside the structure.

A preferred embodiment of the present invention is illustrated in the accompanying drawings, in which:

Fig. 1 is a perspective view of the assembled game structure;

Fig. 2 is a transverse sectional elevation of the structure shown in Fig. 1;

Fig. 3 is a detailed perspective view of the chimney element of the structure;

Fig. 4 is a sectional view taken on the line 4—4 of Fig. 2, omitting the roof elements;

Fig. 5 is a perspective view of a floor member used as one of the marble-conducting elements for the structure;

Fig. 6 is a perspective view of locking device or an assembly member for the structure;

Fig. 7 is a perspective view of a porch or gallery member providing the marble-receiving compartments of the structure;

Fig. 8 is an elevation of the walls of the structure in flat, demounted condition;

Fig. 9 is a perspective view of a marble deflecting member and assembly element of the structure; and

Fig. 10 is bottom view of the roof member for the novel structure, showing the tie trusses therefor.

The gaming device of the present invention is preferably in the form of a demountable toy house, and comprises a wall structure 1, including the front 1a, ends 1b and 1c and back 1d; a gallery or porch member 2; a roof 3; a floor 4; and a chimney 5. The roof 3 is provided on its underside with tie-trusses 3a and 3b as seen in Fig. 10 which are adapted to notchedly engage

2

each other to retain the hinged roof in peaked arrangement as shown in Fig. 2. The chimney 5 is provided with a reduced portion 5a at the lower end thereof, which reduced portion is adapted to be inserted and be retained in an aperture 3c in the roof 3. Gallery member 2 is provided with a pair of hooks 8 which are adapted for insertion into suitable openings therefor provided in the front wall member 1a.

10 The elevated floor 4 is supported within the erected wall structure 1, in inclined disposition toward the gallery 2. Wall member 1a is provided with a plurality of apertures 11a, 11b, 11c, 11d and 11e, opening onto the gallery 2 above the front of said floor, as shown in Figs. 1 and 2. Floor member 4 has a plurality of deflectors 4a, 4b, 4c, 4d, 4e, and 4f fixed to the upper surface thereof as shown in Fig. 5, these deflectors serving to form guide paths to the apertures 1a to 1e and to the marble-receiving compartments 2a, 2b, 2c, 2d and 2e on the gallery 2. It will be apparent from the foregoing description and from the several views in the drawing that a ball or marble placed or dropped on the floor 4 will roll toward and through one of the apertures 1a to 1e and into one of the compartments on the gallery 2.

25 Chimney 5 is provided with a concentric passage 6, which may be cylindrical as shown having sufficient clearance for the free passage of a ball or marble therethrough. Immediately beneath the passage, and in substantially vertical alignment therewith, is a rounded impact member or deflector 7a secured to impactor support 7 and positioned in the line of fall of any marble or ball which may be dropped through the passage 6. Impactor support 7 is preferably inclined inwardly from the gallery-supporting front wall 1a and thus is inclined in a direction opposite to the 30 direction of inclination of the floor 4. As shown in Figs. 2 and 4, support 7 at its outer end, is notched or dove-tailed into a cross slot 14 in the said gallery-supporting wall 1a of the structure, while its inner end is supported in spaced relation to the floor 4 by a detachable spacer piece 9 having notched ends locking in key-slots 15 in said support and 16 in said floor 4. Outwardly of the impact member 7a, the impactor support 7 is provided with a port 7b of sufficient diameter 35 to permit the free passage of a ball or marble, and rearwardly of the impact member 7a the impactor support is provided with a plurality of buttons 7c as may be seen in Fig. 9.

40 The structural units of the improved game apparatus may be produced from a semi-rigid sheet

material such as cardboard or other material having sufficient strength to provide self-support in the assembled structure. The balls or marbles and preferably the impact members, the deflectors and the buttons are preferably made of a more rigid and durable material.

The several disassembled units or elements of the structure may be packed flatwise in a game box; the wall elements being hingedly connected by flexible tapes 10, cemented thereto, and the roof sides being similarly hinged at the peak by a tape 12. The individual units may be easily assembled by a child in erecting the building structure. The hinging tapes 10 and 12 may be attached by the maker or by the user of the game in erecting the structure. For compact packaging, at least one of the wall elements, for example the back wall 1d, should be disconnected.

The marble game is played as follows: A marble or ball 13 is dropped into the chimney 5 through the port 6 through which it falls easily and drops onto impact member 7a. Impact member 7a is rounded on top, and the ball is thus deflected therefrom and falls onto the floor 4 where it rolls downwardly toward the gallery 2. The ball encounters one or more of the deflectors 4a to 4f and is directed thereby to one of the apertures 1a to 1e, passing therethrough into the corresponding receiving compartment on the gallery 2, defined by the partitions 17 (Fig. 7). As will be noted in Figs. 1 and 8, the apertures 1a to 1e are each surmounted by suitable scoring indicia. It will be apparent that the novel device may be used by any number of players to provide an interesting and competitive game when each contestant is supplied with a specified number of balls or marbles which are used to produce and compute a total score. As has been stated herein before, the port 7b on impact support 7 is of sufficient diameter to permit the free passage of a ball or marble therethrough. It will be apparent from the several views of the drawing, and particularly from the views shown in Figs. 2 and 4, that a ball deflected forwardly from the button 7a falling through the port 7b will generally be directed into aperture 11c, thereby obtaining the highest possible score for a single ball.

The provision of a marble game structure in the form of a demountable toy house enhances

the interest of children in using the game and develops skills in assembling and disassembling the separable elements of the structure.

Although the invention has been described and illustrated in connection with certain specific embodiments thereof, it will be appreciated that many modifications may be made therein without departing from the scope of the invention as defined in the appended claim.

10 I claim:

A game structure for marbles and the like, comprising a vertical conductor adapted for the passage of spherical objects in free fall therethrough, diverging means beyond said conductor in said fall-path, an inclined platform below said diverging means in said fall-path adapted to arrest said fall, a plurality of deflector members at the lower extremity of inclination of said platform forming converging runways therebetween, a receiving platform adjacent the restricted ends of said runways, and an aperture adapted for the passage of said spherical objects intermediate each of said ends and said platform, said structure being in the form of a building and having wall members, a removable chimney constituting said vertical conductor, a removable support for said diverging means, a removable spacer piece for holding said support in elevated position with respect to said platform, said diverging means having a rounded impact surface, and said removable support having a port therethrough for passing an object deflected from said impact surface, a removable interior elevated floor constituting said inclined platform, a removable exterior gallery constituting said receiving platform, and means holding said removable elements in assembled position.

RALPH A. KITSON.
